AUTOMOBILE WIND DEFLECTOR

Harold J. Klones, Edmonds, Wash., assignor to Airlite Plastics Incorporated, Everett, Wash.

Filed Apr. 21, 1972, Ser. No. 246,508

Term of patent 14 years

Int. Cl. D12—16
U.S. Cl. D12—181

FIG. 1 is an isometric view of an automobile wind deflector showing my new design;

FIG. 2 is a front elevational view thereof;

FIG. 3 is a rear elevational view thereof;

FIG. 4 is a left end elevational view thereof; and

FIG. 5 is a right end elevational view thereof.

I claim:

The ornamental design for an automobile wind deflector, as shown.
